LAVATORY FITTING OR SIMILAR ARTICLE

Frederick Gordon Mackay and Gerald W. Schmidt, Tarzana, Calif., assignors to Price-Pfister Brass Mfg. Co., Los Angeles, Calif., a corporation of California

Filed Apr. 8, 1963, Ser. No. 74,348

Term of patent 14 years

(Cl. D91—3)

FIGURE 1 is a side elevational view of a lavatory fitting or similar article incorporating our new design;

FIG. 2 is a top plan view thereof taken in the direction indicated by the arrow 2 in FIG. 1; and

FIGS. 3 and 4 are front and rear elevational views thereof.

We claim:

The ornamental design for a lavatory fitting or similar article, substantially as shown.
